ARMAND JACQUELIN, OF PARIS, FRANCE.

WASHING APPARATUS WITH MULTIPLE ASCENDING CURRENTS.

Application filed December 28, 1921. Serial No. 525,435.

To all whom it may concern:

Be it known that I, ARMAND JACQUELIN, citizen of the Republic of France, residing at 11 Avenue Pasteur, Paris, France, have 5 invented certain new and useful Improvements in Washing Apparatus with Multiple Ascending Currents, of which the following is a specification, reference being had therein to the accompanying drawing.

10 My invention relates to a separator of exceedingly simple construction, having vertical ascending currents, which makes it possible to separate in a single operation two products of different specific gravities 15 contained in the state of a mixture in any desired raw material. It is more particularly applicable to the washing of fuels and ores, and to the recovery of useful products contained even in a small proportion in 20 waste products of various kinds, such as for instance ashes from steam boilers, waste products from mines, quarries and various industries.

The apparatus chiefly comprises a washing vat fed from a constant level tank, this vat being in communication with a certain number of funnels into which are discharged the various categories obtained by a preliminary separation of the raw material to 25 be washed, these funnels being provided with adjustable overflows for discharging into the open, and which afford passage to the liquid carrying the products of smaller specific gravity.

30 Several embodiments of the apparatus according to my invention are illustrated by way of example in the accompanying drawings, in which

Figure 1 shows in plan a general arrangement of a complete washing apparatus, of small weight and overall dimensions, easily portable.

Figure 2 is a central longitudinal section along line 2-2 of Figure 1.

45 Figures 3 and 4 are cross-sections in vertical planes respectively along lines 3-3 and 4-4 of Figure 1.

Figure 5 is a detail view on an enlarged scale.

50 For the purposes of description, the various elements of the separating apparatus,

Figures 1-5, may be combined in the following manner: the washing vat proper, the parts which supply to this vat the products to be washed, the parts which supply the 55 washing water and the various elements which ensure the discharge of the washed products.

The so-called washing vat 1, is a box of parallelopiped shape, divided by vertical 60 partitions 5, 6 . . . into a certain number of chambers, 2, 3, 4 . . . in open communication with each other at the bottom.

Through the cover 7 of the vat pass a number 65 of rectangular vertical funnels 8, 9, 10, 11, 12, 13 . . . called washing funnels, arranged tandem in the direction of the length of the vat, or in groups of two or more. In the construction as shown, the 70 washing vat comprises six funnels following each other in groups of two in the direction of the length of the said vat, each group occupying the whole of its width.

Each funnel is provided with a variable 75 level overflow constituted simply by a vertical metal sheet or plate 14, 15, 16, 17, 18, 19 . . . which can slide between two cheeks on one of the walls of the funnels.

One of the overflow devices is shown in detail in Figure 5; the movable plate 14 is provided with two elongated grooves 26 with which engage fixing screws or bolts 27.

The lower part of each funnel is widened so as to facilitate the admission thereto of 85 the ascending currents.

The upper part of each funnel, which is widened at the side opposite the discharging device, is connected by a suitably inclined channel or chute 20, 21, 22, 23, 24, 25 . . . 90 to the outlet of the sieves of a separator screen 28 of a suitable type fed by a bucket elevator 29. This screen could be preferably of "light shape" occupying little space and ensuring as complete removal of dust as possible and a very good separation or classification.

In choosing the width of the funnels it is necessary to take into account the average size of the corresponding category of grains and their proportion in the whole of the raw material; this width varies in the same direction 100

as the said two factors. The height of the funnels varies in the same direction as that of the average limit speed of the corresponding category of grains.

5 By limit speed is understood the uniform speed attained at the end of a certain period of time by any body dropping in a liquid; this speed is a function of the specific gravity and of the diameter of the body in question, assumed to be practically spherical. The limit speed depends moreover on the density of the liquid, and on a special coefficient which is a function of the general shape of the body.

15 A decanting or settling vat 30 surrounds the washing vat 1 on two of its faces.

The parts supplying water to the washing vat, comprise a tank 35 in which the level of water remains constant in spite of any possible variations of the output of the feed pump 36 driven by the motor 32. This tank has at the top a series of overflow channels 37, 38, 39, 40, 41 etc. secured to the walls of the said tank; the edges of the said channels 25 are in one and the same horizontal plane, and each of them constitutes a separate overflow. A protecting case 42 is arranged in front of the outlet of the said channels and guides the overflow water into the decanting or settling vat 30.

A horizontal perforated metal plate or sheet 43 extends throughout the whole of the cross-section of the vat 35, preferably a little below the overflows.

35 The vat 35 is connected to the feed pump 36 by means of a box 44 forming an extension of the upper part of the vat, into which the pump delivers at 45 direct, and without any special piping, the water drawn direct 40 on one of the walls of the suction vat 46. The latter is on the other hand in communication with the part of the settling vat 30 situated under the screen; a metal grating 49 forms a suction strainer.

45 The constant level feed tank 35 is connected to the washing vat 1 by a conduit 47 which opens at 48 at the level of the bottom of the said vat.

The various elements which ensure the 50 discharge of the washed products, are the following: Filtering sieves 50, 51, 52 . . . are arranged under the overflows 14, 15, 16, 17 . . . of the funnels 8, 9, 10, 11, 12 . . . and are extended by draining sieves 60, 61, 55 62, 63 . . . terminating in discharge channels 70, 71, 72, 73 . . .

The washing vat 1 is on the other hand in communication at its bottom at 77, with the lip of a bucket elevator 78.

60 The working of the separating apparatus described in the foregoing will be readily understood on examining the path followed by the products to be separated, and the circulation of the water.

65 The raw products are lifted by the bucket

elevator 29 to the separating screen 28. On leaving the said screen, the products separated into several categories in accordance with their diameter are conveyed by the channels 20, 21, 22, 23, 24, 25 . . . to the 70 corresponding funnels and fall into water, at the side opposite to the overflows, with a speed considerably greater than their limit speed, in a zone where the water is comparatively still owing to the widening of the 75 upper part of the funnels at the side opposite to the overflows.

The grains of the various products having different densities, which constitute the raw mixture to be treated, drop independent of 80 each other into the current of water ascending from each funnel. Therefore, the grains having the smallest density δ have reached the speed v when they reach that portion of the funnel, having a constant cross-section, 85 whereas the grains having the greater density Δ have reached the speed V under the same conditions. Consequently, if one regulates the position of the overflow relative to the funnel in such a way, that the current of 90 water ascending in this funnel has a speed intermediate between v and V in that portion of the funnel having a constant cross-section, the ascending current will take along the grains of the smaller density δ and discharge them by the overflow, while the 95 grains of the greater density Δ will continue to fall in the opposite direction against the current and will drop to the bottom of the vat. Thus, one obtains the separation into 100 two groups of different densities of the raw mixture admitted to the upper portions of the funnels.

When the products to be washed contain a certain proportion of flat products, which is 105 frequently so in the case of coal, it is advisable to effect first a double separation, first according to the diameter and then the thickness. This latter separation could be obtained by means of special grates or grids. 110

The light products of the specific gravity δ escape with the washing water current through the overflows 14, 15, 16, 17, 18, 19 . . . and drop on the filtering sieves 50, 51, 52, 53 . . ., then proceed to the draining sieves 115 60, 61, 62, 63 . . . and are finally discharged through the channels 70, 71, 72, 73 etc. and collected outside the washing apparatus.

Some of the heavy products of the specific 120 gravity Δ drop direct on the lip 77 of the bucket elevator 78, and others on the bottom of the washing vat 1. These latter are thus in front of the opening 48 establishing communication between the washing vat and its feed tank and are carried by the 125 current of washing water into the lip 77 of the bucket elevator.

The dust coming from the screen 28, is not washed and drops direct into the discharge channel 75. The same applies to the 130

higher category of preliminary separation, the light products of which are removed by hand from the channel 76, the heavy products flowing to the buckets of the elevator 78.

5 Any debris carried away by the filtering and drainage water, settles in the settling vat 30 and is subsequently discharged by any suitable means.

10 The circulation of the washing water takes place in the following manner. The water is drawn in at 46 by the pump 36 driven by the motor 32. The water is delivered through the union 45 into the intermediate tank 44 and thence into the constant 15 level tank 35. The whole of the intermediate tank 44 and grating 43 of the tank 35 constitutes thus a device "deadening" the water current.

20 Any excess water delivered by the pump 36, that would have the tendency to change the level in the tank 35 relatively to the predetermined level, is discharged into the channels 37, 38, 39, 40, 41 etc. over the edges of the latter, forming as many independent 25 overflows, then drops into the settling vat 30. The overflow from the said vat is also returned to the suction 46 of the pump through the metal grating 49 forming a suction strainer.

30 In that way a substantially constant level is obtained in the tank 35. Consequently, the various currents escaping under the pressure of a constant column of water, have a great regularity of speed.

35 The water from the tank 35 flows through the conduit 47 and the orifice 48 into the washing vat 1. There, the liquid current becomes divided into various ascending currents which pass up into each of the funnels 8, 9, 10, 11, 12. . . . These elementary currents meet the products to be treated, separate them into products of the specific gravity δ and into products of the specific 40 gravity Δ , and carry away with them through the overflows 14, 15, 16, 17, 18. . . . the products of the specific gravity δ which are stopped by the sieves 50, 51, 52, 53. . . . The water escapes through the said sieves 45 and is collected in the settling vat.

50 The level of the overflows 14, 15, 16, 17, 18, 19 being variable and adjustable at will, it is possible to regulate the speed of the ascending currents which pass through the vertical funnels.

55 In the drawings, the overflows are assumed to occupy the whole length of each funnel, but they could also occupy only a portion of the said length or may be arranged in the direction of the width. For those of the funnels, through which pass water currents of low speed, it is advisable in fact to reduce the width of the overflows, in order that the thickness of the layer of water above the said overflows should remain deep enough 60 to prevent any slight instantaneous varia-

tions, always possible, of the upper level of discharge, from exercising any material influence on the speed of circulation of the water in the funnels, and consequently on the regulation of position of the detachable 70 plates 14, 15, 16, 17, 18. . . . constituting variable level overflows.

The partitions 5, 6. . . . which divide the washing vat into chambers 2, 3, 4. . . . facilitate the settling of the heavy elements. 75

The current of water passing through the orifice 48, also results in driving into the lip 77 of the bucket elevator 78, the heavy products deposited on the bottom of the washing vat.

80 The chief advantages of the washing apparatus above described are as follows:

1. Possibility of simultaneously washing by the method of ascending currents, the various categories of sizes into which it is 85 desired to separate, first by screening, the raw product to be washed.

2. Possibility of collecting separately or in groups of two or more, the light categories which are the useful products when it is a 90 question of fuels.

3. Great simplicity of construction and of working.

4. Absence of any generation of dust, the path of the products being short, and there 95 being no considerable shocks.

5. Combined with a special screen, with a device for a complete preliminary separation of dust, very light and consuming very little motive power, the washing apparatus 100 can work in a closed circuit of washing liquid and be built in the form of a portable apparatus comprising not only the screen 28, but also the circulating pump 36, the motor 32 and its various transmissions, the settling 105 tank 30 and the bucket elevators 29 and 70 for charging the screen and discharging the heavy products.

I claim as my invention:

1. In a washing apparatus with multiple 110 ascending currents, the combination of a constant level reservoir, a washing tank communicating with the said reservoir, partitions in said tank forming adjacent chambers in communication with each other at 115 their lower ends, funnels adapted to receive the raw mixture to be treated and mounted on the said tank above the said chambers in free communication therewith, and overflows adjustably mounted in the open air 120 on the said funnels and forming a discharge-passage for the washing medium containing the particles of smaller density.

2. In a washing apparatus with multiple 125 ascending currents, the combination of a constant level reservoir, a washing tank communicating with the said reservoir, a plurality of funnels adapted to receive the raw mixture to be treated and mounted on the said washing tank in free communication 130

therewith, each of the said funnels comprising an expanding lower and upper portion and an intermediate portion of constant cross-section; an overflow adjustably mounted in the open air on each of the said funnels and forming a discharge-passage containing the particles of smaller density.

In testimony whereof I hereunto affix my signature in the presence of two witnesses.

ARMAND JACQUELIN.
